UNITED STATES PATENT OFFICE.

THOMAS HIPWELL, OF ALLEGHENY, ASSIGNOR TO THE PITTSBURG BRASS COMPANY, OF PITTSBURG, PENNSYLVANIA.

LIQUID-MEASURE INDICATOR.

SPECIFICATION forming part of Letters Patent No. 439,508, dated October 28, 1890.

Application filed February 3, 1890. Serial No. 339,109. (No model.)

To all whom it may concern:

Be it known that I, THOMAS HIPWELL, of Allegheny, in the county of Allegheny and State of Pennsylvania, have invented a new and useful Improvement in Liquid-Measure Indicators; and I do hereby declare the following to be a full, clear, and exact description thereof.

My invention relates to Liquid-measure indicators—that is, to a form of gage by which the quantity of any liquid contained in a vessel may be ascertained by the movement of an indicator-finger over the face of a graduated dial.

My invention has for its object to provide an indicator which is suited not only for registering the quantity of liquid contained in large tanks and casks, but also one which may be constructed of such dimensions as to be especially well adapted to be used in connection with small vessels, such, for instance, as the fount of a lamp. The prevailing form of lamps as now manufactured are chiefly formed of brass, and in order to give a very large and brilliant flame the burners are often constructed proportionately large. Such a flame consumes a great quantity of oil and necessitates the employment of a very large fount or bowl, some being capable of holding 30 a gallon of oil. The founts being formed of brass or other opaque material do not permit of ascertaining from the exterior of the fount just how much oil it contains, while to lift the fount from the hanger and shake it to find how much it contains is a very indefinite and inconvenient mode of ascertaining the amount.

My invention comprises, generally stated, a dial, a tubular case extending down, therefrom and having a slot therein, a guide-rod journaled in the case and connected to the indicating-finger of the dial, and a float encircling the case and having a guide-finger entering the slot and engaging with the guide-rod, a large float being thus employed which is guided in its movement by the case which it encircles and which only engages with the guide-rod by a finger entering the slot, friction between the parts being avoided.

To enable others skilled in the art to make

and use my invention, I will describe the same more fully, referring to the accompanying drawings, in which—

Figure 1 is a sectional view of my improved indicator situated within the fount of a lamp, 55 partly broken away, the spiral guide-rod being shown in full lines. Fig. 2 is a vertical central section of the indicator. Fig. 3 is a cross-section on the line 3 3, Fig. 2. Fig. 4 is a plan view, and Fig. 5 is a modified form 60 of my invention.

Like letters of reference indicate like parts in each view.

I have illustrated my invention, and will describe the same in connection with its application to the fount of a lamp; but it is apparent that it may be applied with advantage to many kinds of vessels.

The dial *a* is made of a size corresponding to the capacity of the lamp-fount to 70 which it is to be applied, and has upon its upper face a graduated scale so marked as to indicate the quantity of oil the fount is capable of holding, and also has points thereon which, in connection with the indicating-finger, as will more fully appear, indicate when the fount is full or empty. The body of the dial *a* has the threaded portion *a'* adapted to engage with the threaded seat *b'* in the top of the fount or bowl *b*. Secured to the dial *a* is 80 the tubular shaft *c*, which passes up through an opening *a*² in the center of the body of said dial. This tubular shaft *c* is provided with the longitudinally-extending slot *c'*, extending from a point just above the base of 85 said shaft to the bottom face of the dial *a*. The shaft *c* is made of such a length that when the dial *a* has been secured in the seat *b'* of the fount *b* its lowest extremity will reach almost to the bottom of the fount. Incased 90 within the tubular shaft *c* is the spiral guide-rod *d*, said spiral rod being journaled at its lower end in the base *c*² of the tubular shaft *c* and the upper end being journaled in the opening *a*³ in the center of the dial *a*. To 95 this end of the spiral guide-rod *d* is secured the indicating-finger *e*. The spiral guide-rod *d* is twisted in proportion to the space which it is desired to have the indicating-finger traverse on the face of the dial. If the dial 100

is only marked to register half of its circumference, it is only necessary for the guide-rod to be twisted half a turn and a proportional increased twist being imparted to the rod according to movement of the finger whether it moves over three-fourths of or over the entire face of the dial. Assuming that the fount shown in the drawings has a capacity of a gallon or eight pints, then the most convenient method is to have the face of the dial accordingly marked off with eight spaces between the points, indicating when the fount is "full" or "empty," and these spaces are numbered accordingly.

15 Below the dial *a* a float *f*, formed of cork or other suitable material, encircles the tubular shaft *c*, being arranged to move readily up and down thereon, said shaft passing through the central seat *f'*, formed in said float *f*.
20 Within the seat *f'* of the float *f* is secured the guide-pin *g*, which engages with the faces of the spiral guide-rod *d* in such a way that when the float *f* is raised or lowered upon the tubular shaft *c* the guide-pin *g*, traveling 25 along the faces of the spiral rod *d*, acts to rotate said rod. The float *f* is held upon the shaft *c* by the guide-pin *g*, which comes in contact with the lower extremity of the slot *c'*.

In Fig. 5 is shown a modified form of my invention in which the rod carrying the indicating-finger is straight instead of spirally twisted, but is flat or angular in cross-section. The slot *c'* in the tubular case is made spiral, and the guide-pin *g* of the float passes through the spiral guideway so formed and engages 35 with the rod, and as the float is raised or lowered it is rotated by the spiral slot and so turns the rod and its indicating-finger.

To illustrate the operation of my improved indicator in its application to the fount of a lamp, let it be assumed that the fount contains no oil, when the float *f* will be at its lowest position on the tubular shaft *c*. The indicating-finger will then register at the point on the dial *a* marked "Empty." Oil is then poured into the fount *b*, and as it rises therein the float *f* is also carried up on the surface of the same, and the guide-pin secured within said float and engaging with the spiral rod *d* 45 acts to turn the said rod *d* and through it moves the indicating-finger *e*. In this way as the oil is introduced into the fount *b* the

spiral rod *d* will travel over the surface of the dial, registering at each mark thereon, until it reaches the point marked "Full." It is then known that the utmost capacity of the fount has been reached and thus there is no danger of filling the fount beyond its capacity and allowing the oil to overflow, not only thereby wasting the oil, but rendering the exterior of the fount oily and disagreeable to handle. When the lamp has been lighted and the oil begins to be consumed, the float will drop accordingly, imparting a steady and gradual rotary movement to the spiral rod *d* and a similar movement to the indicating-finger *e*, and when it reaches the point marked "7" it indicates that there still remain within the fount seven pints of oil. As the oil diminishes within the fount, so the finger *e* keeps rotating, 70 registering the gradual decrease in the amount thereof until the float has reached its extreme position on the shaft *c*, when the finger *e* will again indicate that the fount is empty. The scale can of course be arranged to register 75 any desired fractions of the contents of the vessel, and the register may be employed with any suitable vessel.

What I claim as my invention, and desire to secure by Letters Patent, is—

1. In a liquid-measure indicator, the combination of a dial, a tubular case extending down therefrom and having a slot therein, an angular rod journaled in the case and carrying the indicating-finger, and a float encircling the case and having a guide pin or finger passing through the slot and engaging with the rod within the case, substantially as and for the purposes set forth.

2. In a liquid-measure indicator, the combination of a dial, a tubular case extending down therefrom and having a slot therein, a spiral guide-rod journaled in said case and carrying an indicating-finger, and a float encircling the case and having a guide pin or finger engaging with the spiral guide-rod, substantially as and for the purposes set forth.

In testimony whereof I, the said THOMAS HIPWELL, have hereunto set my hand.

THOMAS HIPWELL.
